DESIGN FOR A HANDLE FOR SCREW DRIVERS AND THE LIKE

John Herbert Abramson, Rockford, Ill., assignor to Greenlee Bros. & Co., Rockford, Ill., a corporation of Illinois

Application February 17, 1939, Serial No. 83,044

Term of patent 7 years

To all whom it may concern:

Be it known that I, John Herbert Abramson, a citizen of the United States, residing at Rockford, in the county of Winnebago and State of Illinois, have invented a new, original, and ornamental Design for a Handle for Screw Drivers and the like, of which the following is a specification, reference being had to the accompanying drawing, forming part thereof.

In the drawing:

Figure 1 is a side view of a handle embodying my new design, the opposite side of the body being substantially identical with that shown;

I claim:

The ornamental design for a handle for screw drivers and the like, substantially as shown and described.

JOHN HERBERT ABRAMSON.
